UNITED STATES PATENT OFFICE.

ALLISON A. PRATT, OF NEW YORK, N. Y., ASSIGNOR, BY MESNE ASSIGNMENTS, TO EDWIN J. SELLEY, OF NEW YORK, N. Y.

INCANDESCENT GAS-BURNER.

SPECIFICATION forming part of Letters Patent No. 780,913, dated January 24, 1905.

Application filed November 23, 1903. Serial No. 182,337.

To all whom it may concern:

Be it known that I, ALLISON A. PRATT, a citizen of the United States, and a resident of the city of New York, borough of Manhattan, 5 in the county and State of New York, have invented a new and Improved Incandescent Gas-Burner, of which the following is a full, clear, and exact description.

The object of the invention is to provide a 10 new and improved incandescent gas-burner arranged to allow minute adjustment for producing a proper mixture of the gas and air, especially by preventing loss of force in the stream of the gas and a swaying thereof from 15 an axial direction to prevent carbonization of the mantle and backflashing of the flame, also to regulate the amount of the light more or less without using the ordinary cock of the gas-fixture.

20 The invention consists of novel features and parts and combinations of the same, as will be more fully described hereinafter and then pointed out in the claims.

A practical embodiment of the invention is 25 represented in the accompanying drawings, forming a part of this specification, in which similar characters of reference indicate corresponding parts in all the views.

Figure 1 is a sectional side elevation of the 30 improvement. Fig. 2 is a like view of the same, showing parts dismembered. Fig. 3 is a sectional plan view of the improvement on the line 3-3 of Fig. 1, and Fig. 4 is a sectional side elevation of a larger-sized extension for 35 the upper mixing-chamber.

The gas-tip A is secured on a gas-supply pipe B, having the usual cock (not shown) for turning on the gas or for shutting it off whenever it is desired to extinguish the flame. The 40 gas-tip A has a conical top A' formed with a central axial jet-opening A², and jet-openings A³ are arranged in the conical sides of the said top A', and on the said tip A screws a regulator C for regulating the amount of gas flowing out of the tip without diminishing the initial pressure of the gas. The regulator C has a contracted top C', forming, with the conical top A' of the tip, an annular passage for

the gas flowing out of the jet-openings A³; but the said contracted top C' does not affect 50 the stream of gas issuing from the central jet-opening A², so that the gas flows from the latter in a straight axial stream upward without the least diminution in its initial pressure as long as the cock in the supply-pipe B is 55 turned on full. By screwing the regulator C upward the annular space between the tops A' and C' is increased, and by screwing the regulator C downward the said space is decreased, and when the regulator reaches a lowermost 60 position then its top C' seats on the top A' above the jet-openings A³, thus completely cutting off the gas from the several jet-openings A³, leaving only the stream of gas issuing 65 from the opening A².

The lower end of the regulator C is provided with an annular flange C², adapted to be taken hold of by the operator for screwing the regulator up or down on the tip A for the purpose above described. The flange C² is 70 provided with apertures and may be seated on the lower end of a compression-cup D, open at the bottom and provided with perforations in the sides for the ready entrance of air, the said cup surrounding the upper end of the 75 regulator and the tip A, and from the top of the cup extends a somewhat contracted neck, D', fitting into the collar E' of a frame E, screwing on the tip A below the regulator and abutting against a shoulder A⁴ on the tip A. 80 Spring-tongues D² on the neck D' press against the inner side of the collar E' to hold the compression-cup in position on the frame E. In case the regulator C is accidentally screwed up until its flange C² abuts against the lower end 85 of the compression-cup then the perforations in the said flange still allow sufficient air to pass into the bottom of the cup to meet all requirements under ordinary pressure; but when the regulator is screwed downward a 90 large amount of air can enter the cup from the open bottom thereof in addition to the air entering through the perforations in the sides of the cup. A spring F, held on the frame E, presses with its free end on the 95 flange C² to hold the same, and consequently

guard the regulator against accidental turning. It is understood that the flange C² is ordinarily below the lower end of the compression-cup.

5 On the collar E' of the frame E screws a tube G, forming at its lower end a lower mixing-chamber G', into which passes the mixture of air and gas from the neck D' of the compression-cup D, and the said tube G is provided in its upper end with an upper mixing-chamber G², connected by a suction-tube H with the lower mixing-chamber G'. The suction-tube H is in the form of an inverted frustum of a cone, extending with its base end a 15 distance up in the chamber G², while the apex end of the said suction-tube opens into the top of the lower mixing-chamber G'. The suction-tube H is provided near its upper end with an annular flange or bead H', seated on the bottom 20 G³ of the upper mixing-chamber G², as plainly indicated in Figs. 1 and 2.

On the upper mixing-chamber G² is exteriorly held a gallery I for supporting a glass chimney J and a rod K, on which a mantle L 25 is suspended, the said mantle fitting with its lower end onto a cap N, provided with the usual wire-gauze N', forming the burner proper, and on which the mixture of gas and air is burned. The cap N is held on the upper end 30 of the extension G⁴ of the mixing-chamber G², the said extension being removably held on a collar I', forming part of the gallery I, and held on the upper mixing-chamber G², as plainly shown in the drawings. The collar 35 I' is provided with integral spring-tongues I² for engaging the extension G⁴ to hold the latter in position when adjusted up or down for increasing or decreasing the size of the mixing-chamber G². Extensions G⁵ (see Fig. 40) of different sizes may be employed on the collar I' to correspondingly increase the size of the upper mixing-chamber G². By the arrangement described the size of the upper mixing-chamber G² can be readily increased 45 in length and diameter to increase the draft when the gas-pressure in the supply-pipe B is low. By having the extensions G⁵ of different diameters different-sized mantles L may be used on the same gas-burner.

50 In using the gas-burner described the cock in the supply-pipe B is turned on full and left so during the time the burner is in use. The gas flowing through the pipe B into the tip A issues through the openings A² A³, and the 55 amount of the gas passing into the compression-cup D is regulated by the operator screwing the regulator C up or down, as previously explained. The gas issuing through the central jet-opening A² with undiminished pressure passes straight up into the lower mixing-chamber G', thus producing a proper inrush of air through the compression-cup without danger of the jet swaying to one side in the chamber G'. It is understood that as long

as the jet passes with full pressure centrally 65 up into the mixing-chamber a proper uniform mixing of the air and gas takes place, and the mixture of air and gas from the lower mixing-chamber G' then rushes through the suction-tube H into the upper mixing-chamber 70 G², from which the mixture of gas and air passes through the wire-gauze N' to be burned in the mantle L. When it is desired to reduce the flame, it is only necessary for the operator to screw the regulator C downward 75 to diminish the gas-supply; but under no circumstances is the position of the cock in the supply-pipe B changed as long as the burner is in use.

It is understood that by having the straight 80 axial stream of gas from the jet-opening A² the outer stream passing through the annular space between the regulator and the top A' is made to conform to the inner stream, and consequently the air is drawn in through the 85 compression-cup D in a uniform manner to insure a proper mixing and proportion of gas and air.

By reference to Fig. 1 it will be seen that as the neck D' of the compression-cup D is 90 contracted the air and gas passing through the said neck readily expands when reaching the larger lower mixing-chamber G', so that a preliminary mixing of the gas and air takes place in the lower mixing-chamber G'. 95

By having the suction-tube H in the form of an inverted frustum of a cone it is evident that as the gas passes through the tube and reaches the upper larger end it expands, and by the suction action the velocity is increased 100 to cause a rapid movement of the gas mixture from the lower mixing-chamber G' through the suction-tube.

The length of the upper mixing-chamber G² can be increased by sliding the extension G⁴ 105 correspondingly upward, so as to increase the draft in case the gas-pressure in the supply-pipe B is reduced.

The incandescent gas-burner shown and described is very simple and durable in construction and can be readily applied to the gas-supply pipe B, and the flame can be instantly regulated without diminishing the pressure of the gas by the operator by screwing the regulator C up or down, according to 110 whether a brighter or less bright flame is desired. By the arrangement described a carbonization of the mantle and the backflashing of the flame is prevented, and consequently 115 a long life is insured to the mantle L. It is 120 understood that the mantle may be supported on a post of magnesium or the like set in a stud or socket held on the wire-gauze N'. 125

The burner above described can be used out of doors as well as in rooms without any protection, such as globes or the like, as ordinary wind-pressure will not extinguish the flame or cause the burner to smoke.

The detail construction of the burner may be varied without deviating from the spirit of my invention.

Having thus described my invention, I claim

5 as new and desire to secure by Letters Patent—

1. An incandescent gas-burner having a gas-tip, a perforated compression-cup open at its bottom and surrounding the tip, and a movable apertured member adapted to be seated

10 on the lower end of the compression-cup, as set forth.

2. An incandescent gas-burner comprising a gas-tip having a central axial jet and side jets, a regulator movable on the tip, to regulate

15 the gas passing out of the side jets, the said regulator having an operating-flange pro-

20 vided with perforations and a perforated com-

pression-cup surrounding the tip and regula-

25 tor and adapted to be partially closed at its

20 lower open end by the said perforated flange,

as set forth.

3. An incandescent gas-burner having a con-

25 ical gas-tip provided with an axial jet at its apex and side jets in its conical sides, a regu-

25 lating-tube surrounding the tip and movable

up and down thereon, the said tube having a

30 contracted apertured top forming an annular

35 passage with the conical tip, and provided

30 a perforated cup surrounding the regulating-

tube and having an open lower end upon which

the flange of the said tube is adapted to be

seated, as set forth.

4. An incandescent gas - burner provided

35 with a lower mixing-chamber, an upper mix-

ing-chamber, a tube of less diameter than the

chambers and connecting the said chambers

40 with each other, and a suction-tube in the

form of an inverted frustum of a cone, and

45 arranged in the connecting-tube with its base

end projecting a distance up into the upper

mixing-chamber, as set forth.

5. An incandescent gas-burner provided

45 with a lower mixing-chamber, an upper mix-

ing-chamber having a slidale extension, and

45 a suction-tube connecting the said chambers

with each other, the tube being in the form

of an inverted frustum of a cone, as set forth.

6. An incandescent gas-burner comprising

50 an upper and a lower mixing-chamber, a com-

pression-cup having a reduced neck opening

into the lower end of the lower mixing-cham-

ber, the compression-cup being open at the

bottom and provided with perforated sides,

55 and a suction-tube in the form of an inverted frustum of a cone, connecting the chambers with each other, as set forth.

7. An incandescent gas-burner comprising

an upper and a lower mixing-chamber, a com-

pression-cup having a reduced neck opening

60 into the lower end of the lower mixing-cham-

ber, the compression-cup being open at the

bottom and provided with perforated sides,

65 a suction - tube in the form of an inverted

frustum of a cone, connecting the chambers with each other, a gas-tip, and a regulator

70 screwing on the tip, for regulating the amount of gas flowing from the tip into the said cup,

the latter surrounding the tip and regulator,

75 and the regulator having a perforated flange,

as set forth.

8. An incandescent gas-burner comprising

an upper and a lower mixing-chamber, a com-

pression-cup having a reduced neck opening

80 into the lower end of the lower mixing-cham-

ber, the compression-cup being open at the

bottom and provided with perforated sides,

85 a suction - tube in the form of an inverted

frustum of a cone, connecting the chambers with each other, a gas-tip, and a regulator

90 screwing on the tip, for regulating the amount of gas flowing from the tip into the said cup,

95 the latter surrounding the tip and regulator,

and a spring for holding the regulator against

accidental movement, as set forth.

In testimony whereof I have signed my name

to this specification in the presence of two sub-

scribing witnesses.
